Patented Dec. 14, 1971

222,727

PHONOGRAPH CONSOLE

William B. Donnelly, Syracuse, N.Y., assignor to
General Electric Company

Filed Nov. 12, 1970, Ser. No. 25,941

Term of patent 14 years

Int. Cl. D14—03

U.S. Cl. D56—4

FIG. 1

FIG. 2

FIG. 3

FIG. 4

FIG. 1 is a front, top and right side perspective view of a phonograph console, showing my new design;

FIG. 2 is a front elevational view;

FIG. 3 is a top plan view; and

FIG. 4 is a side elevational view, the opposite side being substantially a mirror image thereof.

I claim:

The ornamental design for a phonograph console, as shown.
